TRANSFER SHEET FOR SHADING SURFACES

Theodore L. Maddock, Cleveland, Ohio, assignor
to Fine Art Manufacturing Company, Cleve-
land, Ohio, a corporation of Ohio

Application November 23, 1938, Serial No. 242,011

2 Claims. (Cl. 41—4.5)

My prior application, Serial No. 204,343, filed April 26th, 1938, shows and describes a method of and means for shading surfaces, comprising causing isolated areas of transferable material regularly arranged on a thin, tough, flexible, transparent sheet of thermo-plastic material to be transferred by pressure on the back of such sheet to an underlying figure to be shaded.

While the parent application referred to is now concerned only with the method of carrying out the operation, it describes the articles used in the performing of such method, comprising a thin transparent cellulose sheet and a peculiar transferable material affixed thereto.

The present application is a continuation of part of the application just mentioned, and relates to the transfer sheet used in carrying out the method. The prior application refers to a transfer sheet of Cellophane, preferably laminated in different directions to prevent curling. While I have produced good results with such sheet, I have found it susceptible to weather conditions, and I now employ a thermo-plastic film of cellulose acetate, making one integral sheet preferably of about twelve one-thousandths of an inch thickness. Such sheet is thin, smooth, flexible and transparent, and by causing proper transferable material to adhere to it, I may use the sheet as an impression member, placing it over the drawing or other matter to be shaded, then, by pressure of the artist's pencil on top of the sheet, transfer shading material to the underlying surface.

Not only has there been difficulty in securing the proper transparent material which will be sufficiently thin and flexible to enable pressure to be readily transmitted, but which will be tough enough to withstand usage and will not warp, crinkle or change its size under weather conditions; or deteriorate with time; but also, it is highly important that the transfer material adhere to the sheet with sufficient rigidity so that it will not be inadvertently displaced or rubbed off in storage. On the other hand, it must not adhere so firmly as to prevent transfer, and must not deteriorate or become hard or glossy with time.

After considerable experimenting, I have discovered a composition which may be handled like printer's ink, and applied by a printing operation to the cellulose film which will not spread after being printed thereon, and will become comparatively dry and effectively retain its position on the sheet, but which may be transferred to the underlying sheet by pressure on top of the film. The composition which I employ, herein-

after mentioned in detail, forms the subject matter of another application of mine.

My transfer sheet is illustrated in the drawing hereof, and is hereafter more fully described, and its essential novel characteristics are set out in the claims.

In the drawing, Fig. 1 is a plan of my cellulose sheet secured to a suitable protection sheet, a portion of the cellulose sheet being turned over for clearness of illustration; Fig. 2 is a diagram on a very enlarged scale, indicating a cross-section of the transfer sheet and protection sheet; Fig. 3 is an illustration of a figure to be shaded; Fig. 4 illustrates the cellulose sheet placed over the drawing of Fig. 3, showing the artist's pencil in the act of transferring material, and showing also some of the material already applied below the sheet; Fig. 5 illustrates the effect on the same picture of transferring shading by a single impression, and by a plurality of impressions out of registration with each other; Figs. 6, 7 and 8 are diagrams illustrating the effect of two applications of the sheet with the transferable material out of registration, whereby shading shown in Fig. 5 is produced; Fig. 9 is a view illustrating my sheet with the transferable material arranged in parallel lines thereon; Fig. 10 is a diagram illustrating a multiple application of the transfer arrangement of Fig. 9 to the underlying sheet.

As shown in Figs. 1 and 2, A indicates a thin, transparent sheet of cellulose acetate film, on one face of which is affixed a set of regularly spaced transferable dots a; B indicates a backing sheet of ordinary paper, having preferably a non-glossy surface, which serves as a protection for the transferable sheet A. The two sheets A and B are shown as suitably secured together by staples C. In place of the spacially arranged dots of Fig. 1, I may employ any suitable pattern of isolated areas as, for example, parallel lines of the material, as indicated in Fig. 9, at a—1 on the sheet A—1.

In use, the surface to be shaded, designated D, usually carrying an outline drawing, as illustrated in Fig. 3, is placed between the sheets A and B, and may be held therein in any suitable manner, as by gummed tape secured to the margin of the transfer sheet and to the adjacent exposed portion of the underlying sheet.

After the surface or figure to be shaded is put into position, the artist simply manipulates his pencil back and forth across the exposed face of the cellulose sheet, the point of the pencil pressing down on it with sufficient pressure to effect

the transfer. With a little practice this may be done very rapidly.

The Fig. 4 indicates by heavy lines F the approximate strokes of the artist's pencil on top of the cellulose placed over the figure to be shaded. However, this is only a conventional illustration, as the pencil is ordinarily manipulated by free hand back and forth; moreover, the smooth surface of the cellulose sheet prevents any substantial adherence of the pencil material, although the region shaded is readily visible to the operator by reason of the impressed dots showing through the transparent sheet rather more blackly than they appear before the pressure is applied. In the manipulation of the pencil back and forth, no particular care need be observed except at the ends of the strokes.

The result of successive pressure of the operator's pencil over successive areas of the 20 parent sheet A of Fig. 1 is to give a stippled effect on the drawing, as shown at G, Fig. 4. By making a second impression from a transfer sheet A, maintained in parallelism, but slightly shifted from that of the preceding impression, I produce 25 the heavier shading indicated at H, Figs. 5 and 6.

If the transfer sheet for the second impression is laid in a somewhat skewed position over the shaded figure, I may produce a fabric effect varied according to the relation of the two 30 impressions. Thus, in Fig. 5 we have on the coat of the figure one form of fabric effect J, where the sheet A bears the relation to the stippled drawing illustrated in Fig. 7 and we have on the necktie of the figure a different fabric effect L, 35 corresponding to the relative positioning indicated in Fig. 8.

Fig. 9 illustrates a cellulose sheet A—1 formed on its under-surface with parallel lines of transfer material. A single impression gives the same 40 appearance to the underlying surface and a double parallel impression out of registration may give a cross-hatched or peculiar appearance, as indicated, for instance, at N in Fig. 10. There is no limit to the effects that can be produced by 45 making successive impressions with differently positioned transfer sheets, or with sheets having different transfer areas.

The character of the transfer sheet is an important factor, as it must be thin enough and 50 flexible enough to allow a ready transmission of the pressure, must be tough enough so as not to

be torn by the artist's pencil moving over it; must lie flat over the figure to be shaded; must have sufficient transparency so that the artist can see the picture below the sheet. The cellulose acetate film which I employ is somewhat similar to film used for making photographic negatives of the non-curling type. While I have obtained the best results with a sheet of .012 of an inch thickness, this may be varied between the limits of .002 of an inch and .015 of an inch.

The transferable material employed on ordinary carbon sheets used in typewriting, etc., will not adhere to the cellulose acetate film. On the other hand, the inks which have been developed for printing on celluloid, Cellophane and other synthetic sheets, will not offset. I have found that I can accomplish excellent results by employing the following material, which forms the subject matter of another application of mine, namely:

Parts	20
Ester gum	4
Linseed varnish	8
Carbon black	4
Orange toner	2
Carnauba wax	1
	25

The above materials are ground together to make a composition of consistency similar to ordinary printer's ink. This material is placed in the fountain of a suitable press, and an imprint is made on the film by an engraved roller carrying whatever figure is to be imprinted, as, for instance, the dots or parallel lines. After the imprinted substance has been allowed to dry, the cellulose sheet carrying the same is secured face 30 down on the protection sheet, and the product is 35 ready for use.

I claim:

1. As a new article of manufacture, a sheet 40 of thin, flexible, transparent cellulose acetate material having on one face isolated areas of a transferable coating comprising ester gum, oily varnish, carbon black and wax.

2. As a new article of manufacture, a film of 45 cellulose acetate having printed on one face isolated areas of a transferable coating comprising substantially four parts ester gum, eight parts linseed varnish, four parts carbon black, one part carnauba wax and two parts orange toner.

50
